Patented May 24, 1966

204,875

CLOTHES HOOK OR THE LIKE

Merrick R. Mohr, 819 NE. 128th St.,
Seattle, Wash. 98125

Filed June 16, 1964, Ser. No. 80,414

Term of patent 14 years

(Cl. D17—12)

Fig. 1.

Fig. 2.

FIGURE 1 is a front, elevational view of a clothes hook or the like embodying my new design; and FIGURE 2 is a side elevational view thereof. The rear surface is plain and unornamented.

I claim:

The ornamental design for a clothes hook or the like, as shown and described.
